(57) **CLAIM**

The ornamental design for a multimedia terminal having image design displayed thereon, as shown and described.

DESCRIPTION

FIG. 1 is a front view of a multimedia terminal having image design displayed thereon showing our new design;

FIG. 2 is another front view thereof;

FIG. 3 is another front view thereof;

FIG. 4 is another front view thereof;

FIG. 5 is another front view thereof;

FIG. 6 is another front view thereof;

FIG. 7 is another front view thereof;

FIG. 8 is another front view thereof;

FIG. 9 is another front view thereof;

FIG. 10 is another front view thereof;

FIG. 11 is another front view thereof; and,

FIG. 12 is another front view thereof.

The broken lines shown in the drawings are for illustrative purposes only and form no part of the claimed design.

The appearance of the animated images sequentially transitions between the images shown in FIGS. 1-12. The process or period in which one image transitions to another forms no part of the claimed design.
